UNITED STATES PATENT OFFICE.

LOUIS J. FREUNDT, OF CHICAGO, ILLINOIS, ASSIGNOR TO AMERICAN CAN COMPANY, OF NEW YORK, N. Y., A CORPORATION OF NEW JERSEY.

DREDGE OR SIFTER-TOP CAN.

1,141,535.

Specification of Letters Patent.

Patented June 1, 1915.

Application filed August 1, 1913. Serial No. 782,417.

To all whom it may concern:

Be it known that I, LOUIS J. FREUNDT, a citizen of the United States, residing in Chicago, in the county of Cook and State of Illinois, have invented a new and useful Improvement in Dredge or Sifter-Top Cans, of which the following is a specification.

This invention relates to improvements in dredge or sifter top cans.

- 10 An object of the invention is to provide a dredge or sifter top can which may be manufactured at a relatively low cost and which is provided with a slidable, perforated cover adapted, in one position, to close completely 15 an opening in the top of the can, which cover may be reversed in position and moved so as to have the perforations therein over said opening in the can top to thereby provide a sifter or dredge.
- 20 The invention furthermore consists in the improvements in the parts and devices and in the novel combinations of the parts and devices as herein shown, described or claimed.

- 25 In the drawing forming a part of this specification, Figure 1 is a top plan view of a can embodying my improvements and showing the cover in place as it would be while the can is being shipped; Fig. 2 is a 30 top plan view of the can with the cover removed; Figs. 3 and 4 are vertical, sectional views taken respectively on the lines 3—3 and 4—4 of Fig. 1; and Fig. 5 is a top plan view of the can showing the cover in a position the reverse of that shown in Fig. 1 and 35 wherein the sifter holes or perforations in the cover are positioned over the opening in the can top.

- In said drawing the improved can is 40 shown as comprising a body member 10 made of sheet metal, paper, or other suitable material, the body member having applied thereto a top 11 countersunk as at 12 and provided with a raised, substantially rectangular, central portion 13, the latter having straight, vertical end walls 14 and under-bent side walls 15. At one end the raised portion 13 is provided with a hole or recess 16 through which the contents of the can 45 may be emptied out. Coöoperating with said raised portion 13 and slidable thereon is a cover or closure 17, the latter corresponding in shape and size to the portion 13 and being provided with inturned side flanges 18 50 which take into the under-cut sides 15. At

one end, the cover 17 is provided with a plurality of perforations or sifter holes 19 and at its other end is provided with a depending stop flange 20 to properly position the cover when it is placed on the portion 13. When the cover 17 is placed on the top 13, as shown in Fig. 1, the hole 16 is completely covered, but when the cover is taken off and reversed, as shown in Fig. 5, the sifter holes 19 are positioned over the hole 16 and if desired the cover 17 may be slid back to the position in dotted lines in Fig. 5 to thereby completely uncover the hole 16 and allow the contents to be poured out.

By forming the raised portion 13 with under-cut sides as above described the same is materially strengthened and stiffened and by forming the cover with inturned sides 18, the cover is also stiffened so that the two parts coöperate to always maintain a close, tight fit which is not materially affected by frequent manipulation of the cover.

Although I have herein shown and described what I now consider the preferred embodiment of my improvements, yet it will be understood that various changes and modifications may be made in the details of construction and arrangement of parts without departing from the spirit of the invention, and all such changes and modifications are contemplated as fall within the scope of the claims appended hereto.

I claim:

1. A top for dredge cans, consisting of a main portion which is bent upward, outward and downward at its edges so as to form a countersunk top surface and a raised grooved flange adapted to receive the upper edge of the can body, the portion of the said top within the raised flange being formed with a raised rectangular portion having under-bent opposite straight sides 15 which extend above the said raised flange, and the top of said raised portion being formed at one end with a hole and being imperforate at the other end; combined with a sliding cover having at opposite sides in-turned straight flanges 18 engaging beneath the said under-bent sides 15 and arranged above the said raised flange, the said cover being reversible, end for end, and being formed at one end with perforations and being imperforate at the other end.

2. A top for dredge cans, consisting of a main portion which is bent upward, outward and downward at its edges so as to form a countersunk top surface and a raised 5 grooved flange adapted to receive the upper edge of the can body, the portion of the said top within the raised flange being formed with a raised rectangular portion having under-bent opposite straight sides 15 which 10 extend above the said raised flange, and the top of said raised portion being formed at one end with a hole and being imperforate at the other end; combined with a sliding cover having at opposite sides inturned straight flanges 18 engaging beneath the 15 said under-bent sides 15 and arranged above the said raised flange, the said cover being reversible, end for end, and being formed at one end with perforations and being imperforate at the other end, the cover being 20 formed at the end remote from the said perforations with the depending flange 20.

Signed this 29 day of July, 1913, in the presence of two witnesses.

LOUIS J. FREUNDT.
